UNITED STATES PATENT OFFICE.

ALBERT K. HOODWIN AND EDWARD J. KIPP, OF MICHIGAN CITY, INDIANA.

PICTURE-FRAME.

1,062,710.

Specification of Letters Patent. Patented May 27, 1913.

Application filed May 17, 1909. Serial No. 496,347.

To all whom it may concern:

Be it known that we, ALBERT K. HOODWIN and EDWARD J. KIPP, citizens of the United States, and residents of Michigan City, in the county of LaPorte and State of Indiana, have invented certain new and useful Improvements in Picture-Frames, of which the following is a specification.

Our invention relates to picture frames and has for its object to provide a frame made out of plurality of fibrous blanks, such as straw board and like suitable material, which when veneered with a suitable paper, may be made to simulate wood.

A further object is to construct a picture frame, which shall be simple in its construction, strong, durable, efficient in its use, and comparatively inexpensive to manufacture.

With these and other objects in view the invention consists of the novel formation of frame hereinafter more fully described and finally pointed out in the claims hereto appended.

Referring to the accompanying drawings forming a part of this specification wherein like characters of reference denote similar parts throughout the several views, Figure 1, is a transverse section in perspective of our improved frame, a portion thereof being shown as veneered. Fig. 2, is a plan view of one of the blanks for the side frame members. Fig. 3, is a plan view of one of the blanks for the end frame members. Fig. 4, is a fragmentary view in perspective of one of the side members set in position in the supporting tray. Fig. 5 is a plan view of our improved frame after it has been assembled and before it is veneered.

In carrying out the aim of our invention, we employ a suitable tray A, which consists of the bottom 1, the upwardly extending sides 2 and the upwardly extending ends 3. This tray is preferably formed of a continuous sheet of suitable fibrous material.

Adapted to be carried by means of the tray like member A and in engagement with the upwardly turned sides 2, is a pair of oppositely disposed side frame members 4, which are beveled in cross section after having been placed in position. These members 4 are each scored as at 5 and 6 thereby dividing the same into three integral sections or sides 7, 8 and 9 as clearly shown in Figs. 1, 2 and 4. These side members 4 having being formed and placed in position in the tray A, as clearly shown in Fig. 4, it will

be observed that the portion marked 7 engages the upwardly extending wall 2 of the tray A, that the portion marked 8 inclines downwardly and that the portion marked 9 is at a right-angle to portion 7 and engages or rests on the bottom 1 of tray A.

The end frame members designated 10 are scored as at 11 and 12 thereby dividing the same to three integral sections or sides designated 13, 14 and 15. These end members 10 when formed and placed in position in the tray A, as clearly shown in Figs. 1 and 5, it will be observed, that the portions 13 thereof will engage the upwardly turned ends 3 of the tray like member A. It will be observed that the members or blanks 4 have their ends beveled or inclined as at 16 from the score 5 and that the ends 17 of portion 7 are at the right angles to the side edge thereof. The end members or blanks 10, also have the ends beveled or inclined from the score 11 as indicated by the reference character 18. The ends of the portion marked 13 are also beveled or inclined as at 20, so that when the ends of the members 4 and 10 meet to form the corner as clearly shown in Fig. 5, the ends of portion 13 will not interfere or strike the end of portions 7 of the side members 4.

After the side and end members 4 and 10 have been placed in position as clearly shown in Fig. 5, they are veneered by means of paper to simulate wood designated 21 as clearly shown in Fig. 1. This paper is glued to the sides and bottom of the tray A, and also to the exposed surface of the members 4 and 10 as clearly shown. The bottom 1 of the tray A is adapted to be provided with a suitable sheet of fibrous material designated 22 such as paper upon which may be painted or printed any suitable scene, picture, illustration, advertisement or the like.

A frame constructed in accordance with our invention it will be observed can be easily and quickly cut out, formed and assembled and at the same time will be neat, attractive in appearance, durable, efficient, and inexpensive in manufacture.

What we claim is:

1. A picture frame comprising a back, upwardly turned sides and ends integral with said back, a pair of oppositely disposed side members abutting against the inner faces of said sides, a pair of oppositely disposed end members abutting against the inner faces of

said ends, said side members and said end members being beveled in cross section and beveled at their ends, and a paper veneer covering the beveled faces of said side members and said end members, said veneer covering also the exterior face of said sides and said ends, and being bent under to engage the bottom of said back.

2. A picture frame comprising a back, upwardly turned sides and ends integral with said back, and inner members within said frame comprising vertical strips abutting against the inner faces of said sides and ends, inclined strips attached to the upper edge of said vertical strips running to a

point in proximity to said back, and horizontal strips attached to said inclined strips abutting against the inner face of said back and running from the inner edge of said inclined strips to a point in proximity to 20 said vertical strips but being disconnected therefrom.

In testimony whereof we have hereunto signed our names to the specification in the presence of two subscribing witnesses.

ALBERT K. HOODWIN.
EDWARD J. KIPP.
